(57) **CLAIM**

The ornamental design for an electronic pen, as shown and described.

DESCRIPTION

FIG. 1 is a front, right side perspective view of an electronic pen according to the present disclosure;

FIG. 2 is a top, rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof in an enlarged scale; and,

FIG. 8 is a bottom plan view thereof in an enlarged scale. The broken lines shown in the drawings depict portions of the electronic pen that form no part of the claimed design.
